UNITED STATES PATENT OFFICE.

FRANZ CECKA, OF CHEMNITZ, GERMANY, ASSIGNOR TO THE FIRM OF SCHUBERT & SALZER MASCHINENFABRIK, AKTIENGESELLSCHAFT, OF CHEMNITZ, GERMANY.

FLAT HOSIERY-FRAME.

1,180,567.

Specification of Letters Patent. Patented Apr. 25, 1916.

Application filed September 8, 1914. Serial No. 860,643.

To all whom it may concern:

Be it known that I, FRANZ CECKA, a citizen of the German Empire, residing at Chemnitz, in the Kingdom of Saxony, Germany, have invented certain new and useful Improvements in Flat Hosiery-Frames; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in flat hosiery frames, and more particularly in flat hosiery frames in which means are provided for deadening the shock of the thread guides. In machines of this class for each of the braking means provided for the different operations special retarding members must be provided for the different operations of the same thread guide. If the operation of the machine is changed, for example if it is changed from operation on the breadth of the heel to the breadth of the whole blank, and the stops are set accordingly, but the operator omits to throw the stop which before was in operative position out of operation, or in the reverse case to change the brakes, the thread guide is arrested at improper time relatively to the path of the retarding devices. The retarding member has the tendency to move through a certain path which depends on the stroke of the sinker cam. If therefore the thread guide is arrested by the stops which have been set in incorrect positions, the driving mechanism of the machine must break.

The object of the present improvements is to provide mechanism for obviating this objection.

With this object in view my invention consists in the matters to be described hereinafter and particularly pointed out in the appended claims, reference being had to the accompanying drawings and the letters of reference marked thereon.

In said drawings Figure 1, is a diagrammatical side view of the left hand part of the mechanism, Fig. 1^a, is a similar side view showing the right hand part of the mechanism, Fig. 2, is a diagrammatical view of the heel portion of a stocking, and Fig.

3, is a section taken on the line 3—3 of Fig. 1^a.

Referring to the example shown in the figures, the slur bar *a* is adapted to be reciprocated from the sinker cam *b* by means of a rod *c*, a rocking lever *d*, and a connecting rod *e*. The slur bar *a* is rigidly connected with a rod *f* which carries thread guide brakes *g* and *g*¹. Parallel to the rod *f* a thread guide bar *h* is mounted in suitable bearings which carries a thread guide *i*. A second thread guide *i*¹ is mounted on a bar *h*¹. On the thread guide bar *h* lugs *n* and *n*¹ are provided which are adapted to be engaged by arms *o* and *o*¹ mounted on the brakes *g* and *g*¹, so as to produce a rigid connection between the slur bar *a* and the thread guide bar. Parallel to the bar *f* a retarding rod *l* is mounted which carries stops *s* and *s*¹ for the brake *g* and stops *s*² and *s*³ for the brake *g*¹. Furthermore the rod *l* is equipped with a stop *p*.

The slur bar *a* and the retarding rod *l* are formed at one of their ends with rack teeth *x*¹ and *y*¹, respectively, and the rack teeth *x*¹ are in mesh with a gear wheel *x* and the rack teeth *y*¹ are in mesh with a gear wheel *y*, the diameter of which is smaller than that of the gear wheel *x*. The said gear wheels are mounted on a common shaft *v*, and they are connected with each other by a friction clutch. In the path of the thread guide bar *h* there are a stationary stop *k* and a movable stop *p*, and in the path of the retarding rod *l* there are stops *r* and *r*¹.

The operation of the mechanism is as follows: In the example shown in the figures two thread guides *i* and *i*¹ are provided, only one of which is normally in operation and reciprocating along the whole breadth *A* of the head of the frame, this being the thread guide *i*, the thread guide bar reciprocating through the path *A*¹. At the beginning of the heel the mechanism must be set in such a way that the thread guide *i* moves only along the path *B*, while the path *C* is traversed by the thread guide *i*¹ which now becomes operative. As the path has thus been changed the retarding mechanism must be thrown into operation at a different moment. For this reason two brakes *g* and *g*¹ are provided on the rod *f* which are adapted to be thrown into connection with the thread guide bar by suitable means. The brake *g* is used when the thread guides *i*¹

move through the whole breadth A of the blank being knitted. Accordingly the stop s^1 is set in such a way, as to take up the movement of the thread guide shortly before the end of the path A¹. The stop s acts in the opposite direction. The brake g^1 provided for knitting the heel co-operates with the stops s^3 and s^2 . If it is desired that the thread guide be operative only 10 along the breadth B of the heel, the heel stop p is set in operative position and the heel brake g^1 is connected with the thread guide bar h . However, if the operator forgets to throw the brake g out of operation, 15 the stop s moving to the left strikes the brake g and tends to shift the latter and the bar h . As the bar is arrested by the stop p , while the rod l tends to continue its movement, the driving mechanism would 20 break, if the gear wheels x and y were rigidly connected with each other. However, as these gear wheels are frictionally connected with each other, the shock is taken up. The gear wheel y is arrested in its 25 movement while the gear wheel x is further rotated by the slur bar moving forward. If the parts are again moved to the right, the rod l strikes against the stop r^1 before the rod a has completed its stroke. As the 30 stroke of the rod l is thus limited the gear wheel y is likewise arrested, while the gear wheel x continues its rotation. Therefore the gear wheels are displaced relatively to each other in the opposite sense as compared 35 to the movement to the left, so that they assume the correct positions.

While in describing the invention reference has been made to an example in which the frictional engagement of the parts is 40 provided between the gear wheels x and y , I wish it to be understood, that my invention is not limited to the mechanism shown in the figures and that various changes may be made within the gist of my invention. 45 For example, the stops or the lugs n may be made shiftable.

I claim herein as my invention:

1. In a flat hosiery frame, the combination with a reciprocating slur connecting bar, and a thread guide yieldingly connected with the slur connecting bar for operation thereby, of a plurality of stop members reciprocating in the same direction as the slur connecting bar and thread guide bar 50 and at a lower speed and disposed in position for being overtaken by said thread guide bar and to retard the same, yielding driving means for the stop members, and end stops for arresting the thread guide bar in different end positions.

2. In a flat hosiery frame, the combination with a reciprocating slur connecting bar, and a thread guide yieldingly connected with the slur connecting bar for operation thereby, of a plurality of pairs of stop members reciprocating in the same direction as the slur connecting bar and thread guide bar and at a lower speed, the stop members of each pair being disposed in position for being overtaken by said thread guide bar 65 and to retard the same respectively when the thread guide bar is moving in opposite directions, yielding driving means for the stop members, and end stops for arresting the thread guide bar in different end positions.

3. In a flat hosiery frame, the combination with a reciprocating slur connecting bar, and a thread guide yieldingly connected with the slur connecting bar for operation thereby, of a plurality of pairs of stop members reciprocating in the same direction as the slur connecting bar and thread guide bar and at a lower speed, the stop members of each pair being disposed in 80 position for being overtaken by said thread guide bar and to retard the same respectively when the thread guide bar is moving in opposite directions, yielding driving means for the stop members, and stops for arresting the thread guide bar in different end positions, and an end stop located in position for arresting the thread guide in initial position and adapted to return the driving means having yielded in correct position.

4. In a flat hosiery frame, the combination with a reciprocating slur connecting bar, and a thread guide yieldingly connected with the slur connecting bar for operation thereby, of a plurality of stop members disposed in position for being overtaken by said thread guide bar and to retard the same, frictionally connected gear wheels interposed between said stop members and the slur connecting bar and adapted to impart to the said stop members reciprocating movement of reduced speed and in the direction of the movement of the slur connecting bar and thread guide bar, and end stops 100 for arresting the thread guide bar in different end positions.

In testimony that I claim the foregoing as my invention, I have signed my name in presence of two subscribing witnesses.

FRANZ CECKA.
